[57] CLAIM

The ornamental design for a control table for spectro photometer, as shown and described.

DESCRIPTION

FIG. 1 is a front, top and left side perspective view of a control table for spectro photometer showing our new design;

FIG. 2 is a front elevational view thereof;

FIG. 3 is a right side elevational view thereof;

FIG. 4 is a top plan view thereof;

FIG. 5 is a rear elevational view thereof;

FIG. 6 is a bottom plan view thereof; and

FIG. 7 is a front perspective view with a cover set, spectro photometer, display, typewriter and keyboard shown in broken lines for environmental purposes thereof.

FIG. 1

FIG. 2

FIG. 3

FIG. 4

FIG. 5

FIG. 6

FIG. 7
